BAG RACK

Charles J. Olund, Cambridge, Minn.

Application February 24, 1939, Serial No. 258,323

7 Claims. (Cl. 312—62)

This invention relates to improvements in bag racks and more particularly to a novel advertising rack of the type disclosed in my Patent 2,075,129 dated March 30, 1937.

5 One of the objects of the invention is to provide a bag rack having vertical partitions adapted to be adjusted relatively to one another and to the side walls of the rack to permit a merchant to make adjustments to accommodate paper bags of various widths.

10 Another object is to supply a rack with adjustable partitions combined with an adjustable front bar that may be shifted by the merchant to accommodate the various positions to which the partitions have been adjusted.

15 A further object is to furnish a rack having novel means for yieldingly moving a pack of bags forwardly into position where the bags may be readily removed.

20 A still further object is to produce a simple and inexpensive rack and yet one which will be exceedingly effective for the purpose for which it is designed.

25 With the foregoing objects outlined and with other objects in view which will appear as the description proceeds, the invention consists in the novel features hereinafter described in detail, illustrated in the accompanying drawing and more particularly pointed out in the appended 30 claims.

In the drawing:

Fig. 1 is a front elevation of the rack partly broken away and in vertical section to facilitate illustration.

35 Fig. 2 is a transverse vertical sectional view of the same taken on the line 2—2 of Fig. 1.

Fig. 3 is a perspective view of one of the adjustable partitions of the rack.

40 Referring to the drawing, it will be noted that substantially all portions of the rack may be formed of sheet metal or of any other suitable material. 4 designates the back wall of the rack which is preferably extended upwardly at 5, above the top 6 of the bag compartment, to provide an ornamental portion adapted to receive advertising or the like.

45 A front wall 7 of less height than the rear wall extends downwardly and outwardly from the front edge of the top 6, and such wall is preferably provided at its upper and lower edge portions with confronting horizontal grooves 8 to facilitate the attachment of advertising cards to the front wall.

50 A bottom 9 has its rear edge portion secured 55 to the lower edge portion of the rear wall, and

it extends forwardly and downwardly to facilitate feeding a pack of bags toward the open portion of the front of the rack.

5 Side walls 10 are rigidly secured to the rear wall, front wall and top.

The parts described above cooperate with substantially wedge-shaped partitions 11 which provide cells of variable width within the rack. Each partition has its rear edge portion bent at right angles thereto to provide an integral back strip 12, that is preferably welded at its upper end portion to an upstanding tab or tongue 13, the latter slidably engaging the rear wall and being confined by an angle iron guide 14 secured to the top by any suitable means such as screws 15.

15 When the screws are removed any one of the partitions may be readily removed from the rack so that the latter may accommodate wider bags than it was originally intended for.

20 The lower end portion of the back strip 12 slidably engages an upstanding flange 16 integral with the bottom 9 and of the same thickness as the tongue 13.

25 The front end portion of the bottom 9 is turned backwardly and downwardly to provide a flange 17 forming a guide for hooks 18 formed at the rear end of the abutment strips 19 secured to the lower portion of the front edges of the partitions 11.

30 The lower end of each partition is provided with an integral shoe 20 that slidably engages the bottom 9.

35 It will be obvious from the foregoing that any one of the partitions may be shifted laterally so as to take care of packs of bags of various widths 35 and from Fig. 1, it will be noted that the lower corner of the bags 21 will come to rest on the abutment strips 19 so that the forward bag of each pack may be readily withdrawn from the rack.

40 In order to prevent the bags from bulging outwardly too far or from falling through the open front of the cabinet, I have provided a bar 22 having a head 23 at one end and a removable nut 24 at the opposite end. Such bar passes through apertures 25 arranged in the front edge portions of the partitions, and at this point it will be noted that each partition as well as each side wall of the cabinet is provided near its front edge with a series of apertures so that the bar may be properly threaded through regardless of the position to which the partitions have been adjusted. Furthermore, this allows the abutment bar to be arranged at an inclination so as to take care of short narrow bags as well as long wide bags. 50 55

For the purpose of urging the pack of bags forwardly, I propose to employ a spring device 26 which may be formed of a piece of wire shaped to provide a fulcrum portion 27, the latter being 5 pivotally mounted in ears 28 forming part of a plate 29 secured to the rear wall of the rack. A coil spring 30 surrounds the fulcrum bar and has its ends respectively engaging the part 26 and the rear wall of the cabinet for the purpose of 10 pushing the lower end of the part 26 forwardly.

Of course, the side walls are provided at their lower ends with abutment strips 31 to cooperate with the strips 19 in supporting the bags.

From the foregoing, it is believed that the 15 construction, use and advantages of my improved bag rack may be readily understood, and I am aware that changes may be made in the details disclosed without departing from the spirit of the invention as expressed in the claims.

20 What I claim and desire to secure by Letters Patent is:

1. A bag rack comprising a rear wall, front wall, side walls, top and bottom, the front wall extending downwardly from the top and being 25 spaced from the bottom to provide an unobstructed opening at the lower portion of the front of the rack, vertical laterally slidable partitions forming part of the rack and arranged between said walls, each partition being slidable relatively 30 to all walls of the rack, abutment strips arranged at the lower portion of the partitions and provided with guide elements, and a guide member arranged at the bottom of the rack and cooperating with said guide elements.

35 2. A bag rack comprising a rear wall, front wall, side walls, top and bottom, the front wall being spaced from the bottom to provide an opening at the lower portion of the front of the rack, and vertical slidable partitions forming part of the rack and arranged between 40 the rack and arranged between said side walls, each of the side walls and each partition being provided near its forward edge with a series of 45 apertures extending lengthwise thereof, and a removable bar extending through certain of said apertures and forming an abutment across the open front portion of the rack.

50 3. A bag rack comprising a rear wall, front wall, side walls, top and bottom, the front wall extending downwardly from the top and being spaced from the bottom to provide an unobstructed opening at the lower portion of the front of the rack, vertical laterally slidable partitions forming part of the rack and arranged between 55 said walls, each partition being slidable relatively to all walls of the rack, a guide member extending lengthwise of the rack at the juncture between the top and rear wall, each partition having a guide element slidably engaging said guide member, a second guide member extending 60 lengthwise of the rack along the forward end of the bottom, and guide elements secured to the lower end portions of the partitions and slidably engaging the second guide member.

4. A bag rack comprising a rear wall, side

walls, a front wall, and a bottom, said front wall being spaced from the bottom to provide an opening at the lower portion of the front of the rack, vertically disposed laterally adjustable partitions arranged in the rack between said side walls, a rearwardly extending guide flange arranged at the forward end portion of the bottom of the rack, and abutment elements secured to the lower end portions of the partitions and having hooks slidably engaging said flange.

5. A bag rack comprising a rear wall, side walls, front wall and a bottom, the lower edge of the front wall being spaced from the bottom to provide an opening at the lower front portion of the rack, vertically disposed laterally adjustable 15 partitions arranged in the rack between said side walls, each side wall and each partition being provided near its front edge with a series of apertures extending lengthwise thereof, and a removable bar extending through certain of said 20 apertures obliquely across the open front portion of the rack.

6. A bag rack comprising a rear wall, front wall, side walls, top and bottom, the front wall extending downwardly from the top and being 25 spaced from the bottom to provide an unobstructed opening at the lower portion of the front of the rack, vertical laterally slidable partitions forming part of the rack and arranged between said walls, each partition being slidable relatively 30 to all walls of the rack, a guide member extending lengthwise of the rack at the juncture between the top and rear wall, a second guide member extending lengthwise of the rack at the front end portion of the bottom, each of said 35 partitions having guide elements slidably engaging said guide members, and a shoe at the lower end of each partition slidably supported by the bottom.

7. A bag rack comprising a rear wall, side 40 walls, a front wall, top and bottom, the lower edge of the front wall being spaced from the bottom to provide an opening across the lower portion of the front of the rack, a guide member extending lengthwise of the rack at the juncture between 45 the top and rear wall, a second guide member extending lengthwise of the rack at the front end portion of the bottom, vertically disposed laterally adjustable partitions arranged in the rack and having at the upper portion of the rear ends 50 thereof guide elements slidably engaging the first-mentioned guide member, shoes at the lower ends of the partitions slidably supported by the bottom, abutment members secured to the lower end portions of the partitions and provided with 55 guide elements slidably engaging the second guide member, each side wall and each partition being provided near its forward edge with a substantially vertically arranged series of apertures, and a removable cross bar extending through certain of 60 said apertures obliquely across the open front portion of the rack.

CHARLES J. OLUND.
